[57] CLAIM

The ornamental design for a telescopic sight mount, as shown and described.

DESCRIPTION

FIG. 1 is a left side elevational view of a telescope sight mount, showing my new design;

FIG. 2 is a top plan view thereof;

FIG. 3 is a front elevational view thereof;

FIG. 4 is a right side elevational view thereof;

FIG. 5 is a bottom plan view thereof;

FIG. 6 is a rear elevational view thereof; and

FIG. 7 is a left side elevational view illustrating an alternative appearance of the telescopic sight mount when the telescopic sight is mounted at an angle different from that shown in FIG. 1.

FIG. 1
